UNITED STATES PATENT OFFICE.

SAMUEL M. STRONG, OF GARDEN CITY, NEW YORK.

RESPIRATION AND PULSE RECORDER.

Application filed January 11, 1922. Serial No. 528,485.

This invention relates to a device or instrument for recording the character of the actions of the heart and respiratory organs of a person.

The primary object of the invention is to provide an instrument which will produce an accurate graphic representation of the rate, rhythm, and force of respiration and pulse of a human being over a short or a long period of time.

My invention also aims to supply a compact instrument which requires no other external source of power to operate it than that furnished by the expansion of the chest during the natural breathing of the person to whom the instrument is applied.

Other objects and novel features of the invention whereby an instrument of simple construction and certain operation is obtained, will appear as the description proceeds.

The invention is described in connection with the accompanying drawings, in which

Figure 1 is a sectional view on the line 1-1 of Figure 2, looking in the direction of the arrows;

Figure 2 is a sectional view on the line 2-2 of Figure 1 looking in the direction of the arrows;

Figure 3 is a sectional view showing the yieldable connection between a spring and drum;

Figure 4 is a sectional view showing the diaphragm construction;

Figure 5 is a view showing the apparatus strapped in place on the body;

Figure 6 is a view of one side of the record strip showing typical markings registering the heart action; and

Figure 7 is a view of the other side of the strip showing typical markings registering the respiration.

Like numerals of reference designate corresponding parts throughout the several views of the drawing.

The numeral 10 designates a substantially rectangular casing having a detachable side plate or cover 11 and a removable top plate 12. A top bearing plate 13 is supported immediately below the top plate 12 by means such as angles 14 having fastening devices 15 passing through the legs thereof and engaging the top bearing plate and end plates 16 of the casing. A main bearing plate is bent so as to provide a horizontal portion 18 arranged in spaced relation to the top bear-

ing plate 13 and a vertical portion 19 adapted to be placed against a side plate of the casing 10. The main bearing plate fits snugly within the casing and one end of the horizontal portion 18 abuts against the cover 11 when the latter is in position. A side bearing plate 20 is located immediately adjacent to the detachable side plate 11 and an intermediate bearing plate 21 is interposed between the bearing plate 20 and the vertical portion 19 of the main bearing plate. It will be understood that the side and intermediate bearing plates are suitably supported in the casing as by means of angles 22, 23 and fastening devices attaching said angles to said bearing plates and the bottom of the casing, respectively. Suitable brackets 24 are secured to the casing 10 and to these brackets are attached bands 25 that pass around the back of the neck preferably adjustable in relation to each other as by means of a buckle 25' whereby the instrument may be supported in correct position. The bands 25^a connecting the lower brackets 24^a preferably include elastic material 25^b in their structure so as to hold the case close to the body for receiving the heart impulses.

In addition to the bands 25, another band 26 is provided which passes across the back of the person to whom the instrument is applied and has thin metallic strips 27 attached thereto at opposite ends. These metallic strips 27 pass through appropriate slots 28 formed in the end walls of the casing and are secured at one end to hollow drums 29 by screws 29'. These drums are rotatably mounted on spindles 30 which pass through the top bearing plate 13 and are provided with heads 31 seated in recesses formed in the top plate 12. The heads 31 are secured from rotation by suitable screws (not shown) which engage threaded apertures in the top bearing plate. A spiral spring 32 is located within each drum 29 and the inner end of this spring is secured to spindle 30 while the outer end thereof is fastened to the drum 29. The lower ends of the spindles 30 are reduced so as to form a reduced extension 33 which joins the body of the spindle in a shoulder 34. A flange element 35 is adapted to close the lower end of each drum and is detachably secured to the drum for rotation therewith. This flange element is provided with a hub having a circular recess in which is inserted the reduced extension 33 of the spindle until the shoulder 34 of the latter

abuts against the inner side of the hub. The hubs of the flange elements 35 are formed with exterior cylindrical journals 37, 38 which are rotatably mounted in the horizontal portion 18 of the main bearing plate. The journal 37 is prolonged to form a shaft 39 having a further bearing in an auxiliary bearing plate 40 which is attached to the vertical portions 19 of the main bearing plate. A bevel gear wheel 41 is mounted on the shaft 39 for rotation therewith.

From the above description it is quite apparent that when the device is in proper adjustment to the body of a person, the springs 32 tend to hold the case to the body and the strength of these springs is preferably selected so that they allow the chest to expand, without interfering with the breathing of the person wearing the device. As the chest expands a pull is exerted on the strips 27 thus revolving the drums 29 and winding up the springs 32. At the same time the rotation of the drums impart similar motion to shaft 39, the bevel gear 41 mounted thereon, and also to the spur gears 42 which are cut on flanges secured to the upper ends of the drums. When the person exhales the springs 32 wind the strips 27 on the drums. In order that the drums may rotate uniformly the gears 42 are connected by spur gears 43, 44 which are secured to shafts 45, 46 respectively. These shafts are journaled in upper bearing plate 13 and the horizontal portion 18 of the main bearing plate. One end of the shaft 46 is extended beyond bearing plate 18 and has a pinion 47 secured thereto for a purpose which will hereinafter appear.

A shaft 48 is provided with polygonal ends which fit within correspondingly shaped holes in the auxiliary bearing plate 40 and the side bearing plate 20, thus restraining the shaft from rotation. On the shaft 48 is rotatably mounted a unit composed of a bevel pinion 49 and a ratchet wheel 50 integral therewith. The bevel pinion 49 meshes with the bevel gear 41 so that rotations imparted to the latter by the oscillatory movements of the drums 29 are communicated to the pinion and ratchet unit. A spur gear 51 rotatively mounted on the shaft 48 adjacent the ratchet wheel 50 has a pawl 52 pivoted thereto, which pawl engages the teeth of the ratchet wheel whereby rotations of the pinion 49 in one direction are transmitted to the gear 51. A shaft 53 arranged below the shaft 48 is rotatably mounted in end bearings provided by the vertical portion 19 of the main bearing plate 13 and the side bearing plate 20. A gear 54 is secured to the shaft 53 near one end and a gear 55 is fastened to the shaft near the other end thereof. A spring barrel 56, comprising a hub portion and a cylindrical flange, is loosely mounted on shaft 53. A

collar 57 pinned to the shaft adjacent the hub of the spring barrel maintains said barrel from lateral displacement in one direction. A spiral spring 58 within the barrel 56 has one end attached to the shaft 53 and the other end is provided with a cam-shaped lug 58^a adapted to engage in a correspondingly shaped recess 58^b formed in the cylindrical flange of the spring barrel. This construction permits the shaft 53 to turn even after the spring has been fully wound, as the lug on the end of the spring will slip out of its recess when excessive stress is exerted on the spring, thus preventing the breaking of the spring. The spring barrel has a gear 59 cut thereon or attached thereto, which meshes with a feed roller pinion 60. The shaft 53 thus drives the pinion 60 through the yieldable connection made by the spring 58 with the spring barrel. The pinion 60 is keyed to a shaft 61 which is rotatably mounted in suitable bearing plates and also carries a feed roller 62 keyed thereto.

The pinion 60 meshes with a gear 63 which is attached to the second hand shaft 64 of a clock mechanism having a balance wheel 65 and an escapement 66. The gear 63 according to this arrangement is constrained by the escapement to move at the rate of one R. P. M. While the ratio of gears 63 and 60 is such that the latter moves at the rate of six R. P. M. As the circumference of the feed roller is 1 1/4 inches, a movement of 7.5 inches per minute is imparted to the paper or record strip 67 passing over the feed roller. The spring and barrel 58, 56 are so constructed that when fully wound up they will afford sufficient power to feed the paper and run the clock mechanism for three minutes, if the person should stop breathing for that length of time. It will be understood that these dimensions are given merely as examples and that any suitable dimensions and ratios may be used without departing from my invention.

The gear wheel 55 drives a gear 68 which is secured to a shaft 69 rotatably mounted in end bearings provided by the main and intermediate bearing plates 19 and 21. A spring barrel 70 is loosely mounted on this shaft and a spiral spring 71 is mounted within the barrel with one end secured to shaft 69 and the outer end is provided with a cam lug engaging in a recess formed in the inner surface of the barrel in a manner similar to that above described in connection with the spring barrel 56. The spring barrel 70 also has secured to it a gear 72 which meshes with a pinion 73 for driving the rewinding spool 74. This spool is keyed to a shaft 75 which is rotatably mounted in end bearings provided in the bearing plates 20 and 21. One end of the shaft 75 projects beyond the bearing plate 21 and has fixed thereto the pinion 73 which, as above de-

scribed, meshes with the gear 72. The spring barrel 70 and spring 71 cooperating therewith are utilized to maintain a turning effort on the rewinding spool 74 through gear 72 and pinion 73, the cam lug of the spring being pulled out of the recess in the barrel before the spring tension becomes great enough to rupture the record strip.

Having described the driving mechanism and the means by which the driving power is obtained from the expansion of the chest, I will now proceed to describe the devices whereby an accurate record is obtained of the actions of the respiratory organs and heart. A rack 76 is slidably mounted in a guide 77 fastened to the horizontal portion 18 of the main bearing plate. This rack engages pinion 47 so that the oscillations of said pinion are converted into reciprocatory movements of the rack. An arm 78 pivotally mounted at one end on the horizontal portion 18 of the main bearing plate carries a respiration recording pen 79 at the other end and is pivotally connected at an intermediate point to the rack 76, so that the reciprocating motion of the rack will impart like movements to the pen; the radius of the arm 78 being comparatively large so that the pen makes a practically straight line across the record strip. A platen 80 is suitably supported within the casing 10 and the record strip 67 passes over the platen in operative relation to the pen 79. The reciprocations of the rack are produced by the oscillations of the drums 29 as transmitted through gears 42, 44, shaft 46 and pinion 47. The extent of these reciprocations depends upon the degree of the expansion and contraction of the chest and therefore the amplitude of vibration of the respiration recording pen as marked on the recording strip will indicate the capacity of the lungs and the character of the lines will indicate any irregularity or defect in the breathing of the person to whom the instrument is applied.

The transmitter which receives the heart pulsations consists of a metallic back 81 pivoted at 82, in the arms of a channel bracket 83 secured to an end plate of the instrument casing, so as to adjust itself to the body. Over the face of this metal back is stretched a flexible diaphragm indicated in dotted lines at 84. The face of the diaphragm is spaced from the back plate which is preferably slightly concave and this space is filled with a liquid. A small tube 85 has a threaded connection with the back plate and communicates at one end with the space between said back plate and diaphragm and at the other end with the interior of a cylinder 86. One end of this cylinder is covered with a flexible diaphragm 87 carrying a light metallic fitting 88 connected to the central part of the diaphragm. The fitting 88 is pro-

vided with spaced projections adapted to receive between them one end of an arm 89 which is pivotally connected thereto. The arm 89 carries at its other end a recording pen 93. A bracket 90 has spaced bearings 70 91 for pivotally mounting the intermediate trunnions 92 of the arm 89. A platen 94 is mounted in the casing 10 in suitable position for supporting the recording strip 67 in writing relation to the pen 93. The tube 85 75 and cylinder 86, as well as the space within the transmitter are filled with liquid. Impulses of the heart are communicated to the diaphragm of the transmitter which in turn transmits like impulses to the liquid in the tube 85. This small tube transmits these impulses to the liquid of the cylinder which operates diaphragm 87 and moves the arm 89 about its vertical trunnions. The pen 93 is thus given oscillatory motion in multiplied form which is recorded on the strip 67. A small cylinder 95 is formed on the metallic back 81 and communicates with the liquid contained in the transmitter by means of small holes 96. This cylinder is internally threaded at 97 for engagement with a screw plug 98, so that the latter may be screwed in or out to adjust the volume of liquid within the apparatus in order to compensate for changes in temperature and return the flexible diaphragm 87 to zero position before a reading is taken.

A paper holder in the form of a spool 99 is rotatably mounted on a shaft 100 supported in bearing plates 20 and 21. The roll of paper or record strip 101 is preferably of such size as to serve for a continuous test of four hours without the necessity of changing rolls.

The paper is fed over pulley 102, to writing platen 94 where it receives the record of the heart action, to rollers 103, 104 which turn the paper over; passes over platen 80 where it receives the respiration record; over roller 105 and thence to feed roller 62 110 to the surface of which it is held by an idler pulley 106 rotatably mounted on a shaft 107. These rollers, pulleys and spool are driven by the spring barrel 56 and constrained to travel at the desired speed 115 through the escapement 66. The feed roller 62 according to the illustrated embodiment of the invention imparts a surface speed to the record strip of 7.5 inches per minute. The record strip passes from the feed roller 119 to the rewinding drum 74 where it is rewound by the tension produced by spring barrel 70.

In order that the spools 74 and 99 may be readily replaced the bearing plate 20 is 125 preferably made in two parts, designated 20¹ and 20². The lower part 20² may be taken out of the casing, upon the removal of side plate 11, independently of the upper part 20¹, so that the spools 74 and 99 may 130

be withdrawn from their shafts and replaced with other spools without disturbing the bearings of the operating shafts provided in the upper part 20' of the side bearing plate.

- 5 According to my invention the record strip is moved at a uniform rate irrespective of the power received from the expansion of the chest. A yieldable connection is inserted in the driving mechanism so that no excessive stresses can be placed on the record strip or other parts of the device. Furthermore accurate records of the actions of the respiratory organs and heart are obtained on the same record strip, the chart of the 10 respiration being on one side and the graph of the heart action being on the other side of the record strip as shown in Figures 6 and 7. Figures 6 and 7 indicate, by way of example, typical markings for pulse and 15 respiration. These markings are preferably on opposite sides of the same strip 67, which may be suitably marked or calibrated, according to the speed with which the strip passes the markers 93 and 79. These strips 20 or portions thereof may serve as permanent records of the physical condition of the person examined.

It will be understood that the particular construction described and shown has been 25 chosen for illustrative purposes merely and that the invention as defined by the claims hereunto appended, may be otherwise embodied and applied, without departing from the spirit and scope thereof.

30 I claim:

1. In an instrument of the class described having a record strip, a spring motor for operating the strip, and means operated by the movement of the chest incident to breathing for winding the spring motor.
2. In an instrument of the class described, the combination of a record strip, and means driven by the movements of the chest incident to breathing for moving said strip in 45 one direction, said means including a yieldable connection.

3. In an instrument of the class described,

the combination of a record strip, a feed roller, means for driving said feed roller including a rotatable shaft, a drum, and a 50 spiral spring having one end thereof secured to said shaft and the other end yieldably engaging said drum, said devices being driven by the movements of the chest incident to breathing for driving said shaft in 55 one direction.

4. In an instrument of the class described, the combination of a record strip, means driven by the movements of the chest incident to breathing for moving said strip in 60 one direction, and an escapement for controlling the rate at which said strip is moved by said means.

5. In an instrument of the class described, the combination with a record strip, of a 65 spring, means driven by the movements of the chest incident to breathing for winding said spring, mechanism driven by said spring for moving said record strip, and devices for controlling the rate at which said strip 70 is moved by said mechanism.

6. In an instrument of the class described, the combination of a record strip, means driven by the movements of the chest incident to breathing for moving said strip in 75 one direction, and a rewinding mechanism for said record strip adapted to exert a substantially constant force thereon.

7. In an instrument of the class described, the combination of a record strip, a feed 80 roller, means for driving said feed roller, a rewinding mechanism operated by the movements of the chest incident to breathing for said record strip, and devices actuated by said means for driving said rewinding mechanism, said devices including a rotatable shaft, a drum, and a spiral spring having one end thereof secured to said shaft and the other end yieldably engaging said 85 drum.

90 In testimony whereof I have affixed my signature.

S. M. STRONG.
